UNITED STATES PATENT OFFICE.

ROBERT F. SAWYER, OF CHICAGO, ILLINOIS.

SWITCH-BOARD FOR ELECTRIC-ARC-LIGHT STATIONS.

SPECIFICATION forming part of Letters Patent No. 453,349, dated June 2, 1891.

Application filed October 23, 1890. Serial No. 369,044. (No model.)

To all whom it may concern:

Be it known that I, ROBERT F. SAWYER, a citizen of the United States, residing at Chicago, in the county of Cook and State of Illinois, have invented certain new and useful Improvements in Switch-Boards for Electric-Arc-Light Stations, of which the following is a specification.

My invention relates to that class of switch-boards serving as a terminal for the wires from one or more generating-dYNAMOS and also as a terminal for the line-circuit wires of the several circuits run by such dynamos with plugs arranged in pairs, one of the pair being connected to the other thereof by a wire adapted to constitute an electric conductor, and both of the plugs being adapted to be inserted through holes in the switch-board in front of the dynamo and line-circuit terminals into and in contact with such terminals respectively, thereby effecting an electric circuit from the generating-dYNAMOS or one of them, through the switch-board to the line-circuit wires. A current of electricity generated by the dynamos so connected with the line-circuit wires will thus extend to the switch-board through or over the plugs and connecting-wires out on the line-circuit and back thereon to the switch-board, and from thence to the dynamo or dynamos.

The object of my invention is to obtain a switch-board of the character named upon which are placed the dynamo-terminals and the line-circuit terminals required, both of such terminals being firmly and rigidly secured to the back of the switch-board and having holes in front thereof through which plugs may be inserted thereinto, such terminals being also adapted to serve as short-circuit terminals to be used in the changes necessarily incident to the employment of switch-boards of this character at electric-arc-light stations, and to obtain a switch-board of the character named which shall be well adapted for the rapid change off and on to the several line-circuits of the several generating dynamos extending from and to such switch-board.

In this invention as in the invention for a switch-board described and claimed in United States Letters Patent No. 437,516, granted to me on the 30th day of September, A. D. 1890, I employ terminals having therein both plain-

contact and spring-contact receptacles for plugs fitting thereinto (hereinafter termed, respectively, "plain-contact terminals" and 55 spring-contact terminals) for both the dynamo-circuits and for the line-circuits, such terminals being secured to the back of the switch-board with openings in front thereof through the switch-board, through which 60 openings the plugs referred to can be placed and inserted in and electrically connected with the several terminals as desired.

I have illustrated my invention by the drawings accompanying and forming a part 65 of this specification, in which—

Figure 1 is a front elevation of a switch-board having thereon terminals for the negative and the positive poles of two dynamos, and terminals for four line-circuits with transfer-plugs, and wires connecting such transfer-plugs in such manner that one of dynamos is represented as running one of the line-circuits and the other of the dynamos running two of the other line-circuits, with the fourth 70 line-circuit idle. Fig. 2 is a front elevation of the switch-board with other transfer-plugwires thereon, such other wires being employed in making changes hereinafter described, necessary in the use of the device; Fig. 3, an elevation 75 showing the back of the switch-board with the several terminals secured thereon, the switches thereof pivoted to the switch-board, and the wires extending from the dynamo to the dynamo-terminals, and the line-circuit wires extending from the line-circuit terminals; Fig. 4, a side elevation of one of the line-circuit terminals; Fig. 5, a perspective view of a dynamo-terminal; Fig. 6, a perspective view of a line-circuit terminal; Fig. 7, a plug adapted 80 to fit into either the spring-contact terminal of the dynamo-terminals or the spring-contact terminal of the line-circuit terminals; Fig. 8, a transfer-plug adapted to fit into the plain-contact terminals of the dynamo and line-circuit terminals; Fig. 9, a diagram illustrating 85 one of the dynamos, the wires extending from the dynamo to the switch-board, the transfer-plug wires extending from the spring-contact terminals of one of the dynamo-terminals to the spring-contact terminals of one of the terminals of line-circuit 3, and also line-circuit 90 3; Fig. 10, a diagram illustrating the dynamo not illustrated in Fig. 9, wires extend- 95 100

ing from the dynamo to the switch-board, a transfer-plug wire extending from the spring-contact terminal of one of the dynamo-terminals to the spring-contact terminals of one of the terminals of line-circuit 4, line-circuit 4, a wire extending from one of the spring-contact terminals, and the other pole thereof, to one of the spring-contact terminals of line-circuit 2, line-circuit 2, and a wire extending from the spring-contact terminal at the other pole of line-circuit 2, to one of the spring-contact terminals of the dynamo; Fig. 11, a diagram illustrating the manner in which line-circuit 3 is run by the same dynamo with which it is run as illustrated in Fig. 9, with the spring-contact plug at one end of one of the transfer-wires, which in Fig. 9 is illustrated as inserted in the switch-board, withdrawn therefrom, and with a transfer-wire having the two plugs thereof inserted, one of them in one of the plain-contact terminals of the dynamo and the other in one of the plain-contact terminals of line-circuit 3; Fig. 12, a diagram illustrating both dynamos, with line-circuits 3 and 4 run by one of them, and line-circuit 2 run by the other of them; and Fig. 13, a diagram illustrating both dynamos with line-circuits 3 and 4 run by the same dynamo which is running such circuits as illustrated in Fig. 12, and line-circuit 2 run by the other one thereof with certain of the transfer-plug wires changed from the position in which they are shown in Fig. 12.

Each of the dynamo-terminals is composed of two stations, duplicates—one for the positive and one for the negative pole or wire of the dynamo. The station is illustrated in perspective in Fig. 4. It is secured to the back of the switch-board, and the wire from the dynamo is secured to it. The circuit-terminals are composed each of four stations—two right-hand and two left-hand ones. One of these stations—a right-hand one—is shown in perspective in Fig. 5. The left-hand stations are, except in being left-handed in the arrangement of the respective parts, like the right-hand ones. The description of a single dynamo-terminal station will therefore answer as a description of all dynamo and circuit terminal stations on the switch-board. As many of such terminals are in practice placed upon the switch-board as are required by the size of the plant. At the line-circuit terminals there are placed pivotal switch-levers adapted to be alternately brought in contact with the right and left handed stations, and to the pivotal point of these switch-levers the negative and positive poles or wires of the line-circuit are electrically connected.

The stations are each composed of a spring-contact terminal and two plain-contact terminals. The plugs, hereinafter described, inserted in the spring-contact terminals, remain in electrical contact with the terminals during the entire time the circuits electrically connected thereby with the dynamo-circuits

are at work, and the use of the spring in these terminals is to render continual electrical contact certain, while the plugs, which are inserted in the plain-contact terminals, are in nearly every case inserted only during the act of changing or making up circuits upon the board, and hence the electrical contact is sufficiently certain without a spring. In so far as the securing an electrical contact between the plugs and the terminals into which such plugs are inserted, the use of the spring-contact terminals is the same as that of the plain-contact terminals. These spring-contact terminals being duplicates and the plain-contact terminals also duplicates, I have used the same letters of reference to indicate the same parts in the terminal station of the dynamo-terminals and the line-circuit terminals.

Like letters and figures refer to like parts throughout the several views.

Y and Z are dynamos.

A is the terminal of dynamo Z, and B the terminal of dynamo Y.

Z' Z² are the wires extending from dynamo Z to terminals A and Y'.

Y² are the wires extending from dynamo Y to terminal B.

C' C² C³ C⁴ are respectively the terminals of line-circuits 1, 2, 3, and 4.

D is a station for the dynamo-terminals, and E a station for the line-circuit terminals.

d is a clamp on dynamo-station D, to which is secured the dynamo-wire. Clamp d is not required on the line-circuit station E, and E' is a projection on the base of the line-circuit station E, which is not required on dynamo-station D. The position of projection E' determines whether the station E is a right-hand station or a left-hand station.

D' is the spring-contact terminal, and D² D² are the plain contact terminals.

d' is the spring in the spring-contact of the terminals D' and E', and d² d² are the holes through which are placed the screws securing the terminal stations D and E, respectively, to the back of the switch-board.

F is a spring-contact transfer-plug, having the handle F', Fig. 6, which is constructed of material of the class known in the art as "non-conducting," and a metal shaft F², secured in the handle F'. Metal shaft F² may have the notch f² therein, when desired, and where this notch f² is used the point f³ caused thereby is adapted to enter a notch or hole provided therefor in spring d'. This notch f² is neither new nor essential, and the hole therefor in the spring d' is not illustrated.

f' is a wire, one end of which is secured, as illustrated in Fig. 6, to the metal shaft F² of spring-contact transfer-plug F, and the other end is secured in like manner to another like spring-contact transfer-plug. The spring-contact dynamo-terminals of the dynamos being like the spring-contact terminals of the several line-circuits, either one of

the spring-contact transfer-plugs F may be inserted in either one of the spring-contact terminals D E.

G is a plain-contact transfer-plug, G' being the handle, and G² the metal shaft, thereof. Shaft G² is adapted to be inserted in plain-contact terminals D² of the dynamo and line-circuit stations, respectively. The metal shaft G² of the plain-contact transfer-plugs are 10 electrically connected by the wire g.

In Figs. 1 and 2 and in the several Figs. 9 to 13, both inclusive, the wires f' and g of Figs. 6 and 7 are lettered w' to w⁴, both inclusive, in order to intelligently describe the 15 several electrical connections, which may be formed by the use of the transfer-plugs when the same are inserted in the face of the switch-board, hereinafter described.

The several stations at the negative and 20 positive terminals in the switch-board being duplicates, I have in Figs. 1, 2, and 3 lettered the negative terminals N and the positive terminals P, (in both the dynamo and line circuit terminals,) and in Figs. 8 to 12, both 25 inclusive, the negative terminals are indicated by the minus sign and the positive terminals by the plus sign, in the usual manner.

H H are the line-circuit switches, which consist of handle h, pivot H', which is rotatable in 30 the switch-board X and firmly secured in plate h', constructed of vulcanized fiber or some suitable non-conducting material, lever H², pivoted at one end thereof on pivot J, and at the other end thereof on pivot h² to non-conducting-plate h', and a lever H³, pivoted midway from the ends thereof on pivot K, and at one end thereof on pivot h³ to non-conducting-plate h'. 35

The lug or projection E' in Figs. 3 and 6 is 40 adapted to be placed in electrical contact with switch-levers H² and H³, or to be released from such electrical contact by the movement of such levers toward the stations E, or away therefrom when the handle h of the switch 45 is turned to the right or to the left, as desired.

The wires of the several line-circuits 1, 2, 3, and 4, are electrically secured to pivots J and K, J being illustrated as at the negative pole and K at the positive pole.

Dynamo Z is represented by full lines in 50 Fig. 1 as running line-circuit 3, one of a pair of spring-contact transfer-plugs connected by wire W' being inserted in the spring-contact terminal of the negative pole of dynamo Z, and the other of such pair being inserted at the negative pole of line-circuit 3 in the spring-contact terminal to the right-hand side of terminal C³, and one of the spring-contact transfer-plugs of the pair attached to wire W² 55 being inserted in the spring-contact terminal of the positive pole of dynamo Z and the other of such pair being inserted at the positive pole of line-circuit 3 in the spring-contact terminal to the right-hand side of terminal C³. The handle h of this line-circuit terminal being thrown to the right, such line-circuits are thereby thrown by levers H² H³ (see

Fig. 3) in electrical contact with the plug-receptacles at the right-hand side of such terminal.

Dynamo Y is represented in Fig. 1 as running line-circuits 2 and 4, one of a pair of spring-contact transfer-plugs connected together by wire W³ being inserted in the spring-contact terminal at the negative pole of terminal B of dynamo Y, and the other of such pair being inserted at the negative pole of line-circuit 2 in the spring-contact terminal at the right-hand side of terminal C², and one of the spring-contact transfer-plugs of the 75 pair connected together by wire W⁴ being inserted at the positive pole of line-circuit 2 in the spring-contact terminal at the right-hand side of such terminal C², and the other one of such pair being inserted at the negative pole of line-circuit 4 in the spring-contact terminal at the right-hand side of terminal C⁴, and one of the spring-contact transfer-plugs of the pair electrically connected by wire W⁵ being inserted at the positive pole of line-circuit 4 in the spring-contact terminal at the right-hand side of such terminal C⁴ with the other of such pair inserted in the spring-contact terminal of the positive pole of dynamo Y at terminal B.

To cut circuit 4 out from dynamo Y and switch such circuit into dynamo Z, the operation performed is as follows: One of the pair of plain-contact transfer-plugs connected by wire W⁶, Figs. 2 and 10, is inserted at terminal A in one of the terminals D² at the positive pole of dynamo Z, and the other of such pair is inserted at the positive pole of line-circuit 3 in one of the plain-contact terminals D² at the right-hand side of terminal C³. 95 The one of the pair of transfer-plugs which are electrically connected by wire W², inserted at the positive pole of line-circuit 3 in the spring-contact terminal at the right-hand side of terminal C³ in Fig. 1, is taken out of the switch-board, and the wire W² thus rendered dead. The wire W⁶ now forms the conductor for line-circuit 3 in place of wire W². The manner in which line-circuit 3 is now 100 electrically connected on the switch-board is 105 illustrated in diagram Fig. 10, wire W² being indicated as "dead" with its lower end free by the dotted lines in such figure. Next the spring-contact transfer-plug at the free end of wire W² is placed in the spring-contact terminal at the positive pole of line-circuit 4 at the left-hand side of terminal C⁴, Fig. 2. Then take one of the pair of plain-contact transfer-plugs connected together by wire W⁷ and place it at the positive pole of circuit 4 in the upper of the plain-contact terminals at the left-hand side of terminal C⁴ and place the other of the pair at the negative pole of said circuit 4 in the lower of the plain-contact terminals at the left-hand side 110 of terminal C⁴, Fig. 2. Then take one of a pair of spring-contact transfer-plugs connected together by wire W⁸ and place it at the negative pole of line-circuit 4 in the 115

spring-contact terminal to the left-hand side of terminal C^4 , and place the other one thereof in the spring-contact terminal at the positive pole of line-circuit 3 at the right-hand side of terminal C^3 , from which has been removed, as described, the spring-contact transfer-plug attached to the lower end of wire W^2 . Then take out the plain-contact plug attached to wire W^6 in the lower plain-contact terminal at the positive pole of circuit 3 at the right-hand side thereof, and also the plain-contact plug at the upper end of wire W^6 in dynamo-terminal A at the positive pole, as indicated by the dotted lines on Fig. 2, extending from wire W^5 , near the ends of such wire. Then place another of the pair of plain-contact transfer-plugs, being one of a pair united by wire W^9 in the plain-contact terminal at the positive pole of line-circuit 4 on the right-hand side thereof, and place the other of such plugs in the plain-contact terminal at the negative pole of said circuit 4 to the right-hand side thereof. Immediately as the last plug is inserted the switch H to circuit 4 is quickly thrown to the left by handle h , and as soon as thrown one of the plain-contact plugs on wire W^7 is withdrawn from the plain-contact terminal in which it is inserted, after which the other of such plugs is removed, as indicated by the dotted lines at terminal C^4 on Fig. 2, and thus wholly removed from the board.

In Fig. 12 a diagram is shown of the manner in which the circuit 4 is, by the operation last above described and in addition to circuit 3, run by dynamo Z, with the wire W^7 shown in dotted lines. There is also shown in this diagram Fig. 12 the manner in which dynamo Y is electrically connected with line-circuit 2, over the wires W^3 , W^4 , W^9 , and W^5 .

To remove the wires W^4 and W^9 from the switch-board and to transfer the plug at the lower end of wire W^5 , now inserted in the spring-contact terminal to the right-hand side at the positive pole of line-circuit 4, and place the same in the spring-contact terminal at the positive pole of the line-circuit 2 at the right-hand side thereof, and so present, when finished, transfer-plugs and connecting-wires, arranged as illustrated by the full lines in diagram Fig. 13, one of the pair of plain-contact transfer-plugs connected together by wire W^{10} is placed in one of the plain-contact terminals to the right-hand side of and at the positive pole of circuit 2, and the other thereof in one of the plain-contact terminals of dynamo-terminal B, as indicated by the dotted line W^{10} , Figs. 2 and 13. By the placing of these plugs on the wire W^{10} , as described, the wires W^5 , W^9 , and W^4 can be

treated as dead-wires, and the spring-contact transfer-plug at the lower end of wire W^5 removed, as indicated by the dotted coil of wire at the lower end of wire W^5 , and placed in the spring-contact terminal at the positive pole of circuit 2, to the right-hand side thereof. The dead-wires W^4 and W^9 may then be taken from the switch-board, as can also the wire W^{10} , thus restoring wire W^5 to life. In Fig. 13 these wires, which are removed, are indicated by dotted lines, as is also so much of wire W^5 as is changed in its position by the last-described operation.

Having thus described my invention, what I claim, and desire to secure by Letters Patent of the United States, is—

1. In a switch-board, a line-circuit terminal consisting of a right-hand terminal for the positive and for the negative pole of the line-circuit and of a left-hand terminal for each of such poles, a pivoted lever electrically connected at its pivoted point with the positive wire of the line-circuit, and a second pivoted lever electrically connected at its pivotal point with the negative wire of the line-circuit, such levers being coupled together, so that the movement of one thereof will produce movement in the other thereof, but such levers not electrically connected, in combination with a dynamo-circuit terminal and transfer-plugs electrically connected in pairs, each of such transfer-plugs being adapted to be electrically connected with the dynamo-circuit terminals and the line-circuit terminals, substantially as described. 95

2. In a switch-board, the combination of dynamo-terminals consisting of a spring-contact and a plain-contact station for the negative and for the positive pole of the dynamo, with line-circuit terminals consisting of a right and a left hand spring-contact and plain-contact station for the negative and positive poles of the line-circuit, transfer-plugs electrically connected in pairs adapted to be inserted in the spring-contact terminals, and other transfer-plugs, also electrically connected in pairs, adapted to be inserted in the plain-contact terminals, a switch-lever electrically connected at its pivotal point with the positive wire of the line-circuit, a second switch-lever electrically connected at its pivotal point with the negative wire of the line-circuit, such levers not electrically connected together, but coupled together, so that the movement of one of them will cause like movement of the other, substantially as described. 110 115
